UNITED STATES PATENT OFFICE.

MARK S. LEVERING, OF PHILADELPHIA, PENNSYLVANIA, ASSIGNOR TO THE STANDARD HOSE MENDER AND PIPE COUPLER COMPANY, OF CAMDEN, NEW JERSEY.

DESIGN FOR A MEMBER FOR HOSE-COUPINGS.

SPECIFICATION forming part of Design No. 33,086, dated August 14, 1900.

Application filed July 3, 1900. Serial No. 22,454. Term of patent 14 years.

To all whom it may concern:

Be it known that I, MARK S. LEVERING, a citizen of the United States, residing at the city of Philadelphia, in the county of Philadelphia and State of Pennsylvania, have invented and produced a new and original design for a Member of a Hose-Coupler, of which the following is a specification, reference being had to the accompanying drawings, forming part hereof, in which—

Figure 1 is a side elevational view of a member of a hose-coupler, showing my design. Fig. 2 is an end elevational view of the same looking from left to right; and Fig. 3 is a view similar to Fig. 2, but looking from right to left.

The leading or material features of my design, as illustrated in the drawings, consists of the configuration or form of the member, which has a cylindrical end A, notched or indented longitudinally, as at a, an intermediate cylindrical portion or neck E, and a ring-shaped end D, merging into the neck E. The cylindrical end A incloses a tube or barrel B, which is concentric with said end A. When viewed in side elevation, as at Fig. 1, the member presents the appearance of two cylinders A and E, of which A is larger in diameter than E and has one end notched or indented, as at a', and the other end

rounded as at a so as to merge into the cylinder E. One end of the cylinder E is enlarged into a ring D. When viewed in end elevation, the left-hand end, as illustrated in Fig. 2, presents the appearance of a series of concentric rings, of which the inner ring d is flat and wide and the outer ring D is also flat and wide. When viewed in end elevation, the right-hand end, as illustrated in Fig. 3, presents the appearance of a ring A divided into a series of segments by the openings a, and concentric with this segmental ring A and surrounded thereby is a second ring B, which has a rounded and beveled appearance. Between the rings A and B is a flat ring C, joining the two rings A and B together.

Having thus described my invention, what I claim as new, and desire to secure by Letters Patent, is—

The design for a member of a hose-coupler, substantially as herein shown and described.

In testimony whereof I have hereunto set my signature at Philadelphia, Pennsylvania, this 2d day of July, A. D. 1900.

MARK S. LEVERING.
